APPARATUS FOR OPERATING ON STRAND
OR STRIP MATERIAL

Norman H. Nye, Cuyahoga Falls, Ohio, assignor to
The Vaughn Machinery Company, Cuyahoga
Falls, Ohio, a corporation of Ohio

Application September 20, 1938, Serial No. 230,773

4 Claims. (Cl. 164—68)

This invention relates to an improved method and apparatus for operating on strand or strip material and more particularly to a method and apparatus of this character for performing successive operations on the material, such as shearing, stamping, perforating or the like.

An object of my invention is to provide improved apparatus for performing operations of the character indicated on strand or strip material at high speed and at accurately spaced points or intervals.

Another object of the invention is to provide improved apparatus for performing such operations on strand or strip material which is in continuous motion, as when such material is being advanced by a feed mechanism or is issuing from a machine in which some other operation or operations have been performed upon it.

Still another object of my invention is to provide novel means whereby the spacing of the operations on the material can be conveniently changed without stopping or interfering with the motion of the strand or strip.

Yet another object of my invention is to provide a novel method of operating on moving strand or strip material by which the spacing of the operations can be varied as desired.

The invention may be further briefly summarized as consisting in certain novel combinations and arrangements of parts hereinafter described and particularly set out in the appended claims.

In the accompanying sheets of drawings, Fig. 1 is a front elevation showing apparatus embodying my invention, but with the strand or strip advancing means omitted;

Fig. 2 is a vertical sectional view taken through the apparatus as indicated by line 2—2 of Fig. 1;

Fig. 3 is another vertical sectional view taken on line 3—3 of Fig. 1;

Fig. 4 is a side elevation of the apparatus;

Fig. 5 is a partial front elevation showing co-operating rotatable work-engaging members of another form which may be used when the material to be operated upon is a wire or strand;

Fig. 6 is a side elevation showing a modified form of the apparatus of my invention; and

Fig. 7 is a side elevation showing still another modification.

In Figs. 1 to 4, inclusive, I show my invention embodied in apparatus to be used for severing or shearing strip material S into sections or lengths, although as indicated above, my invention is not limited to the operation being a shearing operation, nor to the operations being performed on strip material. The embodiment of

my apparatus here illustrated includes material advancing means 10, a shearing mechanism 11 to which the strip material is fed or supplied by the advancing means and variable power transmission apparatus 12 which can be adjusted for controlling or determining the lengths of the sections to be sheared from the strip material.

The material advancing means 10 may comprise a pair of cooperating feed rolls 14 and 15 which grip the strip of material S to feed or advance the same, although in some instances the material advancing means may be some other apparatus for performing manufacturing operations on the strip and from which the strip issues after the performance of such operations. In the material advancing means 10 the cooperating feed rolls 14 and 15 may be mounted in a suitable frame or stand 16 and may be driven by gearing 17 which is connected with an electric motor 18 by a worm 19 or other equivalent means.

The shearing mechanism 11 may comprise a frame or stand 21 having a pair of rotatable blade holders 22 and 23 journaled therein and connected with each other by suitable gears 24 and 25. Tool members such as the shear blades 26 and 27 are mounted on the holders and are adapted to cooperate with each other to sever the strip S upon each revolution of the holders. Suitable work guiding and supporting means, such as the tables or platforms 28 and 29 may be arranged on opposite sides of the shearing mechanism 11 for supporting the strip and the sections or lengths which are severed therefrom.

The present apparatus is capable of operating on the strip S to cause the shear blades 26 and 27 to cut the strip into lengths or sections while it is being continuously advanced and to permit operation of the apparatus in this manner I provide means for driving the shear blades such that whenever they meet to sever the material their velocity will be equal to the velocity of travel of the strip. In other words, the shear blades are so driven that they will be moving at substantially the same speed as the strip at the instant that the blades engage and sever the strip.

It will be seen, however, that if the rate of advance of the strip is constant and the angular velocity of the shear blades remains constant during a complete revolution thereof, the lengths or sections severed from the strip will be fixed and will not be subject to change or variation. In order that variable lengths may be sheared from the strip I provide the variable drive mech-

anism 12, by which the shear blades can be driven in a manner to cut longer or shorter sections from the strip as may be desired. Since the shear blades travel at the same speed as the strip 5 at the time of severance it is necessary that the velocity of the shear blades be increased or decreased during the portion of their revolution in which they do not come in contact with the material if sections of variable length are to be cut.

10 It is also necessary that the revolutions per minute of the shear blades be varied with respect to the rate of advance of the strip if the shearing mechanism 12 is to be capable of cutting several different lengths or sections. As will 15 be presently explained in detail the driving mechanism 12 provides for such variation in the angular velocity of the shear blades and also provides for variation in the revolutions per minute of the shear blades, so that sections of various 20 lengths can be cut from the strip material S while the same is being advanced at a given constant rate.

The variable speed drive mechanism 12 may include an upright frame 31 and a bracket or 25 mount 32 shiftable on the frame and having journaled therein a shaft 33 through which the power is transmitted for driving the shear blade holders 22 and 23. The shaft 33 lies in the same vertical plane as the axes of the shear blade 30 holders but, as will be explained more in detail hereinafter, is adapted to be shifted in such plane by adjustment of the mount 32 for varying the extent to which its axis is offset from the axis of the shear blade holder 22.

35 For connecting the inner or adjacent end of the shaft 33 with the shear blade holder 22, I provide means which operates to vary the angular velocity of the shear blades during each revolution thereof. This connecting means may comprise a crank pin 35 which is connected with the shear blade holder 22 at a fixed moment arm or crank arm distance from its axis of rotation and a member 36 connected with the inner end of the shaft 33 and which is engaged by the crank pin 35 with provision for relative shifting therebetween. The crank pin 35 may be connected with the shear blade holder 22 by providing the latter with a disk or plate member 37 outwardly of the gear 24 and on which the crank pin may be mounted. The member 36 may also be a disk which is connected with the shaft 33 and has a transverse slot or guideway 38 formed in the inner face thereof. A block or bearing member 39 is slidable in this slot and has an opening 50 therein in which the crank pin 35 engages.

The mount 32 may be adjustably connected with the frame 12 in any suitable manner, for example, the frame may be provided with guideways in which a base or flange portion of the 60 mount slidably operates. A spindle 40 may have a screw connection with the mount 32 and may be arranged to be rotated by the handwheel 41 to cause lifting or lowering of the mount on the frame.

65 As will be seen from the arrangement just described the mount 32 can be lifted or lowered to thereby vary the extent to which the shaft 33 is offset from the axis of rotation of the crank pin 35. It will also be seen that when the mount 70 32 is adjusted to a position with the shaft 33 in alignment with the axis of the shear blade holder 22, the crank will be driven at a constant or uniform angular velocity which is the same as the angular velocity of the disk 36. However, 75 when the mount 32 is shifted to an offset position

for the shaft 33, such as that shown in Fig. 1, the rotation of the disk 36 will cause the shear blade holders to be rotated at varying angular velocity. For such an offset relative position of the shaft 33 the shear blades will be driven at their minimum angular velocity during the moment that they cooperate in shearing the strip. Immediately following such shearing of the strip the blades will be driven with accelerating angular velocity until they reach the 180° position opposite their shearing position whereupon their angular velocity will decelerate until the shearing position is again reached at which time the blades should have a speed of travel equal to the rate of advance of the material.

10 If desired, indicating means may be provided for facilitating the adjustment of the mount 32. Such indicating means may comprise a pointer 42 connected with the mount and graduation on the frame with which the pointer cooperates. During such rotation of the disk 36 the bearing block 39 will have more or less reciprocable sliding movement in the groove 38.

15 Power for operating the shearing mechanism 12 may be taken from the motor 18, or in other words, from the same power device which drives the strip advancing means 16 and may be supplied to the shaft 33 through a selective speed ratio device whereby the revolutions per minute of the shear blades can be varied with respect to the rate of advance of the strip S. This selective speed ratio device may be in the form of a friction drive as shown in Figs. 1 and 4 and which may comprise a friction faced disk or transmission member 43 mounted on the outer end of the shaft 33 and a friction disk or roller 44 which cooperates therewith. The disk 44 may be journaled in an auxiliary housing portion 45 of the frame 12 and may be connected with the motor 18 through the strip advancing means by a shaft 46 and bevel gearing or the like 48 contained in the auxiliary housing portion 45.

20 The arrangement for the friction disk 44 and the auxiliary housing portion 45 is such that the point at which the disk 44 engages the friction face of the main disk 43 will be spaced from the axis of the shaft 33 at exactly the same distance as the crank pin 35 when the latter is at the lowermost point of its arcuate travel. This relation is important because it establishes a desired 25 driving relation such that the speed of the shear blades at the time that they come into shearing engagement with each other will be exactly equal to the velocity of travel of the strip.

25 From the construction and arrangement above described for the transmission mechanism 12, it will be seen that the shear blades can be driven at an angular velocity which varies during each revolution and that the revolutions per minute of the shear blades can be varied with respect to the rate of advance of the strip. Since the power for operating the shear blade holders 22 and 23 is transmitted from the strip advancing means 16 it will also be seen that the revolutions per minute at which the shear blade holders are 30 driven will be proportional to the speed of advance of the strip. When the mount 32 is adjusted to vary the angular speed of the shear blades the speed ratio or setting between the disks 43 and 44 is also automatically changed. Thus, when 35 shorter sections are to be sheared from the strip the mount 32 is lowered on the frame 12. This will cause the crank pin 35 to operate with a greater offset between its rotation axis and the axis of the shaft 33 and this will result in a greater 40

change in the angular velocity of the shear blades. This same adjustment of the mount 32 will cause the point of contact between the disks 43 and 44 to approach nearer the axis of the shaft 33 and this will result in the shear blades being driven at a faster R. P. M. When sections of greater length are to be sheared from the strip the mount 32 is adjusted upwardly in the frame 12 and this will result in a smaller change in the angular velocity of the shear blades and will result in a ratio or setting between the disks 43 and 44 such that the shear blades will be driven at a lower R. P. M.

Instead of providing my improved apparatus 5 with the shear blades 26 and 27 for severing the strip into sections, I may provide cooperating work-engaging members or blades 50 and 51, as shown in Fig. 5, which may have niches or recesses 52 in their cooperating edges. The members 50 and 51 may be used when the material 0 to be operated upon is a strand which is to be severed, partially severed, or otherwise operated upon at spaced intervals.

In Fig. 6 of the drawings I show a modified 5 form of my apparatus for operating on strand or strip material and which is capable of operating on such material in substantially the same manner and for the same purposes as the apparatus of Figs. 1 to 4. The apparatus of Fig. 0 6 differs from that of Fig. 1 in that the friction disks 43 and 44 are omitted and a positive drive is used in place thereof. This positive drive may include a gear 55 mounted on the outer end of the shaft 33a and a worm 56 15 cooperating with such gear. In this form of my apparatus, as in the form previously described, the power for driving the shaft 33a and the shear blades is supplied from the strip advancing means 10a which is located ahead of the shear mechanism. Power may be transmitted from the strand advancing means 10a to the worm 56 by means of suitable shafting 57 having flexible couplings or universal joints 58 20 therein.

To provide for varying the revolutions of the 15 shear blades with respect to the rate of advance of the strip material S', I may employ change speed mechanism through which the power for driving the shaft 33a may be transmitted at different selected ratios. This change speed 25 mechanism may comprise a gear box 60 having a suitable arrangement of gearing therein affording a selection of the desired different gear ratios. Operating levers 61 and 62 may be provided on the box for shifting to the different settings or 30 gear ratios and the box may also have indications 63 thereon for designating the positions of the levers for the different ratios.

The transmission mechanism 12a has a shift- 35 able mount 32a thereon, corresponding with the shiftable mount of the transmission mechanism of Fig. 1, and vertical adjustment or shifting of the mount for varying the angular acceleration of the shear blades is permitted by the flexible 40 couplings or universal joints 58 in the shafting 57. The mount 32a may have a pointer 64 thereon which cooperates with graduations or 45 indicators 65 on the frame 31a for indicating different settings to which the mount 32a may be shifted and which correspond with different 50 settings or ratios of the gear box 60. Thus by appropriate adjustment sections of the desired length can be cut from the strip S'.

In Fig. 7 I show still another form of my apparatus in which the transmission mechanism 75

12b does not have a drive connection to the strip advancing means 10b, but has an individual driving means such as the electric motor 67. In this form of my apparatus the shiftable mount 32b in which the shaft 33b is journaled is constructed with a motor support or bracket 68 thereon. The shaft 33b may be driven from the motor 67 through a worm 69 and a gear 70 mounted on the outer end of the shaft 33b and with which the worm cooperates. It will 10 be understood, of course, that the shaft 33b transmits power to the rotary shear blade holders of a strip shearing mechanism similar to the mechanism 11 of Fig. 1 and that the shear blades will be driven at varying angular velocities, de- 15 pending upon the setting or adjustment of the mount 32b.

In order to provide for variation in the revolutions per minute of the shear blades for the purpose above explained, I use a variable speed 20 motor as the driving motor 67 and control the speed of operation of the motor in accordance with the setting or adjustment of the mount 32b. For this purpose I provide an electric control device or rheostat 70 which can be adjusted 25 for different motor speeds by swinging of the arm or lever 71. By means of a link 72, this lever may be connected with some portion of the mount 32b, such as the projecting lug or bracket 30 73.

With this arrangement it will be seen that when adjustment is to be made for the shearing of sections of a different length from the strip S' the mount 32b is shifted upwardly or downwardly, as desired, to thereby change the ad- 35 justment of the transmission mechanism for varying the angular velocity at which the shear blades are driven. This adjustment of the mount 32b also causes motion to be transmitted through the link 72 to the rheostat arm 71 and to shift the setting of the rheostat 70 to a corresponding setting at which the motor 67 will be driven at the appropriate speed to provide the required number of revolutions per minute 40 of the shear blades for severing sections of the 45 desired length from the strip. For convenience in adjusting the transmission mechanism, the mount 32b may have a suitable pointer 74 connected therewith and the frame may be provided with graduations or indications 75 with which 50 the pointer cooperates.

In describing the construction and operation of the different forms of my improved apparatus for operating on strand or strip material, it has been assumed that the strip or strand will ordinarily be advanced at a constant rate and that the angular velocity and revolutions per minute of the shear blades, or other cooperating rotative tools, are to be varied for changing the spacing of the operations performed on the material. However, I wish to make clear that all 55 of the various forms of my apparatus can be operated continuously at a given number of revolutions per minute for the shear blades or tools and the rate of advance of the material 60 can be varied to secure different spacings in the operations performed on the material.

From the foregoing description and accompanying drawings it will now be readily understood that I have provided an improved method 70 and apparatus for operating on strand or strip material whereby the material can be sheared or otherwise operated upon while in motion and the spacing of the operations can be conveniently varied. It will be seen furthermore that my im- 75

proved apparatus embodies novel means for varying the angular velocity of the cooperating shear blades or tools during each revolution thereof and also embodies novel means for varying the revolutions per minute of such shear blades or tools. It will also be understood that in my improved apparatus the shear blades or tools will be driven at exactly the same speed as the material at the instant of engagement of such blades or tools with the moving material and that this will insure accurate and satisfactory operations on the material without producing buckling or kinking therein.

While I have illustrated and described the method and apparatus of my invention in a somewhat detailed manner, it will be understood of course that the invention is not to be regarded as limited to the exact steps of procedure and details of construction herein disclosed, but includes such changes and modifications as come within the scope of the appended claims and do not constitute a departure from the spirit of the invention.

Having thus described my invention, I claim:

- 25 1. In apparatus of the character described, the combination of material advancing means, cooperating rotative members adapted to perform successive operations on the material being advanced, and power transmission means connecting the material advancing means with the rotative members comprising a crank rotatable about a fixed axis, a rotatable driving element engaging the crank with provision for relative shifting therebetween, a movable support for said rotatable driving element whereby the axis of the latter may be displaced with respect to said fixed axis, and cooperating friction drive members, one of which is journaled in a fixed support and the other of which is connected with 30 said rotatable driving element and relatively adjustable upon shifting of said movable support.
- 25 2. In apparatus of the character described, the combination of cooperating rotative members adapted to perform successive operations on a strand or strip of moving material, driving means for the rotative members including a crank ro-

tatable about an axis and a rotatable driving element for the crank, a movable support for said driving element whereby the axis thereof may be displaced with respect to the axis of the crank, a variable speed electric motor connected with said driving element, and means responsive to variation in the position of the movable support for controlling the speed of the electric motor.

3. In apparatus of the character having a pair of cooperating rotative tool members adapted to operate on strand or strip material while the latter is being advanced, means operable to drive said tool members and to vary the spacing of the operations performed on the material comprising a pair of rotatable drive members having cooperating pin and slot elements and one of which is shiftable for varying the angular speed of the tool members and another pair of cooperating rotatable drive members one of which is shiftable for varying the speed ratio and the revolutions per minute of said tool members, a shaft connecting the shiftable members of said pairs, and a bearing mounting said shaft and shiftable to cause simultaneous adjustment of said shiftable members.

4. In apparatus of the character having a pair of cooperating rotative tool members adapted to operate on strand or strip material while the latter is being advanced, means operable to drive said tool members and to vary the spacing of the operations performed on the material comprising a rotatable slotted member, a crank connected with one of said tool members and having a pin engaging in the slot of the slotted member, a rotatable transmission member, a shaft connecting said slotted member for rotation with said transmission member, a rotatable drive member having driving engagement with said transmission member at substantially the same radial distance from the axis of said shaft as that at which said pin engages in said slot, and means mounting said shaft and providing for simultaneous adjustment of said slotted and transmission members.

NORMAN H. NYE.
